Patented June 28, 1927.

UNITED STATES PATENT OFFICE.

WILLIAM WILSON, OF BROOKLYN, NEW YORK.

COMPRESSOR APPARATUS.

Application filed April 28, 1926. Serial No. 105,273.

My invention relates to a compressor of the type wherein the compressor piston is operated by a motor through the medium of reduction gearing, and is particularly though 5 not exclusively adaptable to household refrigerating machines. Its object is to provide a practical method of effecting the required reduction from motor speed to piston speed, and at the same time of permitting a 10 duplex arrangement of cylinders in a compact and economical construction. Another object is to prevent the infiltration of oil from the gear casing into the cylinder.

The following drawings disclose one of the 15 various mechanical forms that may be embodied in the principle of this invention:

Figure 1 is a front sectional elevation of my invention, showing the gearing, cylinder, and compressing mechanism.

20 Figure 2 is a side sectional elevation of such apparatus, illustrating a duplex arrangement of cylinders, one of which is shown in detail, the other being suggested in outline form.

25 In the drawings, 1 is the gear casing, and 2 the pedestal, which is here shown as an integral part of the casing. There are two sets of bearings, designated by the numerals 3 and 4 respectively. Bearings 3 support the 30 motor shaft 5, which extends through the stuffing box gland 6 and the packing 7 within the stuffing box 8, and through the opening 9 in the said casing. The stuffing box gland is secured to the casing by bolts 10.

35 The worm gear 11 is suitably fixed to the shaft 5, and so positioned as to engage the worm wheel 12 fixed on to the shaft 13, which is supported by bearings 4. At the extremities of shaft 13, and suitably attached thereto, are cranks 14 and 15. These cranks engage the connecting rods 16 and 17, respectively, and these are attached to their corresponding pistons 18 and 19. The cylinders 20 and 21 are equipped with suction pipe 40 openings 22 and discharge pipe openings 23. Each piston has a suction valve 24 working 45 against a spring 25; and each cylinder has a discharge valve 26 working against a spring 27 abutting against the cylinder head 50 28.

Communicating between the suction pipe openings 22 and the interior of the casing, are balanced pressure ports 29, each comprising a channel 30 and a one-way valve 31 con-

sisting of a valve seat 32, a ball 33, and a 55 spring 34.

The casing 1 is sealed with a cover plate 35 upon which are mounted the said cylinders, which are secured thereto by bolts 36.

The motor, situated outside of the said 60 apparatus, motivates the shaft 5, which in turn actuates the reciprocating pistons 18 and 19, through the medium of the reduction gears 11 and 12, the shaft 13, the cranks 14 and 15, and the connecting rods 16 and 17. 65 On the downward or suction stroke of the piston, the working fluid enters through suction openings 22 and through the open suction valve 24, and into the cylinder above the piston. On the upward or compression 70 stroke, the valve 24 closes, and the discharge valve 26 opens, thus forcing the fluid out through the discharge opening 23.

In apparatus of this type, it is generally required to effect a reduction of the motor 75 speed to that required for the practical operation of the compressor piston. This is frequently accomplished with bevel gears, but in such a construction, the axis of the driving gear intersects with the axis of the 80 driven gear, so that duplex operation is impracticable, especially where the apparatus must be compact, as in household refrigerating machines. In my invention, however, the common axis of the bearings 3 is at an 85 angle to and does not intersect with the common axis of the bearings 4; so that shaft 13 can be extended to operate any number of cylinders; the desired reduction in speed being effected by the worm gearing system 90 above described.

95 Duplex operation and the required speed reduction can be accomplished by the use of a train of spur gears and pinions; but such an arrangement would of necessity require a deeper gear case, and hence a more space-consuming apparatus than with an arrangement of bearings and worm gears such as is embodied in my invention.

In this apparatus, the gear case is partially filled with oil, for lubricating purposes. Because of the pressure differential existing between the gear casing and the cylinder, some of the oil in the gear casing is frequently drawn up into the cylinder by the 100 piston. To eliminate this occurrence, the suction pipe openings 22 are connected to the interior of the gear casing by com-

municating channels 29, which remove said pressure differential and serve to create a balanced pressure, thus preventing the oil from being drawn up into the cylinder by the piston.

In a design of piston having two sets of piston rings, such as are shown in Fig. 1, the lower portion of the piston is generally lubricated by the splash system, and the upper portion by means of an independent lubrication system, such as oil cups positioned on the outside of the cylinder. In this invention, however, the communicating port 29 serves the additional purpose of allowing sufficient oil to be drawn up through the valve 31 to lubricate the said upper portion of the piston. This is rendered feasible by the arrangement of ball valve 31, the straight channel 30 without any pockets or traps, and the reduced central portion of the piston.

In refrigerating machines of the air-cooled, low-pressure type, fluids are often used that have a deteriorating effect on the insulation of an electric motor. For this reason it is desirable in such cases to keep the motor removed from such fluids. In this invention, the motor is positioned outside of the gear casing, so that said fluids cannot possibly reach it; and at the same time making possible ready access to said motor.

What I claim is:

1. In a compressor apparatus, the combination of a compressor cylinder and a gear casing, said cylinder being suitably attached to and opening into said casing; said cylinder containing suitably situated suction and discharge pipe openings, and communicating channels contained within and forming an integral part of the said

cylinder wall, and positioned between said suction pipe openings and the interior of said casing, each of said channels containing a one-way valve, whereby the fluid is permitted to flow from said casing towards said suction pipe openings.

2. A compressor apparatus comprising an enclosed, hollow, gear casing; a stuffing box positioned on the outer surface of said casing; a motor shaft extending through said stuffing box and into said casing; a cylinder suitably attached and opening into said casing; said cylinder containing suitably situated suction and discharge pipe openings; a piston with a central portion of reduced cross-sectional area, the upper edge of said piston on the down stroke thereof remaining above the upper edge of said suction pipe opening; and communicating channels contained within and forming an integral part of the said cylinder wall, and positioned between said suction pipe openings and the interior of said casing, each of said channels containing a one-way valve, whereby the fluid is permitted to flow from said casing towards said suction pipe openings.

3. In a compressor apparatus a compressor cylinder suitably mounted upon and opening into a crank case, said cylinder containing within its wall a suitably situated suction pipe opening, and a laterally enclosed open-ended duct communicating between said suction pipe opening and said crank case, said duct being in part of enlarged cross-sectional area and containing within said enlarged portion a one-way valve whereby fluid is permitted to flow from the said casing towards said suction pipe openings.

In testimony whereof I affix my signature.

WILLIAM WILSON.
